United States Patent

Des. 234,689
Patented Apr. 1, 1975

234,689

VEHICLE WASH INSTALLATION

James E. Widner, Grandview, Mo., assignor to
Robo Wash, Inc., Kansas City, Mo.

Filed Dec. 4, 1972, Ser. No. 311,686

Term of patent 14 years

Int. Cl. D25—03

U.S. Cl. D13—1 B

Fig. 1.

Fig. 4.

Fig. 3.

Fig. 2.

FIG. 1 is a prospective view of a vehicle wash installation embodying my design.

FIG. 2 is a front elevational view thereof.

FIG. 3 is a side elevational view thereof, the other side being a mirror image.

FIG. 4 is a top plan view thereof.

I claim:

The ornamental design for a vehicle wash installation, as shown and described.
